United States Patent Office.

JOSEPH HODGSON, OF PHILADELPHIA, PENNSYLVANIA, ASSIGNOR TO
THOMAS DOLAN, OF SAME PLACE.

Design No. 4,526, dated December 20, 1870.

DESIGN FOR A WOVEN SHAWL-FABRIC.

The Schedule referred to in these Letters Patent and making part of the same.

I, JOSEPH HODGSON, of Philadelphia, county of Philadelphia, State of Pennsylvania, have invented produced a Design for Woven Shawl-Fabric, of which the following is a specification.

The figure in the accompanying drawing represents the design as it appears when drawn on pattern-designer's paper.

The design consists of broad and narrow inclined lines, the continuity of some of which is interrupted by line x so as to give the pattern a somewhat angular appearance.

The fabric is woven in a loom, twenty-four harnesses and fifty-six bars being used.

Irrespective of the colors employed,
I claim—

The design for a woven shawl-fabric, substantially as described and illustrated in and by the accompanying drawing.

In testimony whereof I have signed my name to this specification in the presence of two subscribing witnesses.

JOSEPH HODGSON.
